United States Patent Office.

ROBERT NEALE, OF BROOKLYN, E. D., NEW YORK.

Letters Patent No. 94,432, dated August 31, 1869.

IMPROVEMENT IN TRANSFER ENGRAVING.

The Schedule referred to in these Letters Patent and making part of the same.

To all whom it may concern:

Be it known that I, ROBERT NEALE, of Brooklyn, E. D., in the county of Kings, and State of New York, have invented and made a new and useful Improvement in Transfer Engraving; and I do hereby declare the following to be a full, clear, and exact description of the said invention, reference being had to the annexed drawing, making part of this specification, wherein—

Figure 1 is an elevation of the engraving-types on one side of the transfer-roller;

Figure 2 is an elevation of the transfer-roller, at the opposite side to the types;

Figure 3 represents one portion of the transfer-roller, with the types in place; and

Figure 4 is a section of the roller and types, at the line $z z$, figs. 1, 2, and 3.

Similar marks of reference denote the same parts.

The object of this invention is to facilitate the engraving of metallic plates, with letters or figures of more or less ornamental character, by the "transfer-process."

To effect this, I make use of hardened movable steel-types, with the letter or figure at the end, and fitted accurately, so that several such types can be set together in a cylinder or roller, to compose the name or characters to be transferred to the plate.

This method of transfer is to be distinguished from that heretofore resorted to, in which the name of a bank, or of an individual, or a group of characters, has been formed in a plate, and then transferred as a whole upon the surface of a roller, and, from that, retransferred to the plate, in the process of engraving.

My improvement dispenses with engraving the entire name or group of characters, and allows the same to be composed in a manner similar to the setting-up of types.

Hence, only an alphabet or set of characters has to be engraved in the beginning, and from the same, when hardened, any desired number of separate types can be obtained.

The original plate, with the letter or character engraved thereon, and afterwards hardened, can be preserved, and employed in making any desired number of types, by transferring the engraving to the end of such types.

The letters or characters heretofore engraved, have either been cut into the surface of the plate, so as to print wholly or partially with ink, or said letters have been left, and the surrounding surface has been cut away, more or less, or formed with lines, so that, in the printing, the letter itself will appear white, or nearly so.

In making use of my improvement, any kind of letter or character may be employed that can be transferred.

My invention is especially designed to facilitate the engraving of names on plates of steel, copper, or other metal for printing, and my improvement can be employed in making name or number-plates. In the first-named instance, the letters on the types will be found to read from left to right. In the last-named instance, the letters on the types will be reversed; and, I remark that the letters or characters themselves may be of any desired kind, according to the use to which they are to be put.

In the drawing—

a is the shaft of the transfer-roller, upon which is a collar, *2*, and nut, *b*, for compressing the heads *c* and *d*, and clamping the types *e* between them.

The heads *c d* are made with projecting ribs, *3* and *4*, either square, as shown, or V-shaped, and the types are made with corresponding grooves.

Two sides of each type are parallel, or nearly so, and the other two are in the plane of the radius of the cylinder, and the bases of the types sit upon the cylindrical portion *5* of the transfer-roller.

In order to press the separate types to each other, and hold them firmly in the direction of the line of types, I make use of the blocks *f* and *g*, and these are attached to the respective heads *c d*, and a screw, *i*, upon a stud that is affixed to the head *c*, is employed to act against the other block *g* and head *c*, to force said block firmly against the end of the line of types.

A pair of levers, with claws at the end, entering holes in the outer sides of the heads *c d*, may be employed to give a partial rotation to said heads, and thereby force the types firmly together.

The types and roller are to be employed in a suitable press, and transferred to the plate by rolling, as usual.

What I claim, and desire to secure by Letters Patent, is—

The method, herein specified, of engraving, by transfer, names and other lines of characters, by means of separate types mounted in a roller, fitted to clamp and hold the same, substantially as set forth.

In witness whereof, I have hereunto set my signature, this 14th day of July, 1869.

ROBERT NEALE.

Witnesses:

CHAS. H. SMITH,
GEO. T. PINCKNEY.
